HORIZONTALLY ADJUSTABLE WINDOW
SHADE BRACKET

George N. Medinger, Baltimore, Md.

Application February 18, 1938, Serial No. 191,158

1 Claim. (Cl. 248—272)

This invention relates to window shade brackets, and especially to an improved horizontally adjustable window shade bracket.

One object of this invention is to provide an improved two-piece bracket including a base to be placed and permanently secured to either one of the interior upright boards or plates of a window frame and formed with a series of closely spaced keepers with which the second piece can 10 be alternatively and interchangeably engaged so as to be supported in a proper and desirable position for pivotally supporting one end of a window-shade roller whose other end is supported by a similar shade-bracket, irrespective of the 15 length of the roller within certain limits.

Another object of the invention is to provide a horizontally adjustable bearing-element, of a window shade bracket, which element can be adjusted by simple manipulation without the use 20 of any tool or implement, and without having to overcome any resistance other than the very light weight of the bearing-element; and which element is securely held in its useful position by the shade-roller engaged therewith in cooperation 25 with the base-plate which is secured to the window-frame.

Other objects and important features are pointed out or implied in the following details of description, in connection with the accompanying 30 drawing in which:

Fig. 1 is a front view showing the front side of two of my improved shade-brackets on the upper ends of the interior upright plates or boards of a window-frame, the actual size being greatly 35 reduced.

Fig. 2 is a view showing a fragment of the interior plate in horizontal section having secured thereto one of my improved shade-brackets, all these parts being greatly enlarged to about twice 40 the length of the actual size used in practice.

Fig. 3 is a view similar to Fig. 2, but the removable and interchangeable part being tilted at an acute angle to the length of the fixed part or base as when being swung to its useful position 45 of Fig. 2, or swung in the opposite direction to the removable position of Fig. 4.

Fig. 4 is a longitudinal sectional view taken along the horizontal line 4—4 of Fig. 1, the removable part in the position to be removed by a lateral movement.

Fig. 5 is a modification showing a base-plate provided with auxiliary fasteners.

Referring to this drawing in detail, in which, 55 similar reference numerals refer to similar parts

in the several views, the invention is described in detail as follows:

The sheet-metal base-plate or base 5 includes feet 6 that are apertured to receive screws or other means for securing them to the frame-plate. Webs 7 unite these feet 6 with the intermediate slotted part 8 of the member or base 5, and are at obtuse angles thereto; the feet being in the same plane, and the said intermediate part being in a plane parallel to that of the feet; so, when the feet are against the window-frame, the intermediate part 8 is spaced from the window-frame for a purpose that will presently appear. The said intermediate part is provided with a series of parallel vertical slots 9 that are separated by a series of narrow and narrowly spaced parallel keepers 10.

The removable shade-roller-connecting member 11 has its outer end portion formed either with an aperture 12 or with an upper notch, according to whether the rotary pivot or the non-rotary end-supporting element of a blind-roller or shade-roller is to be engaged therewith; and its inner end or attaching end is provided with an angular attaching finger 13 that is bent near its base so its main part is at right angles to and projecting laterally from the main portion of this member 11. Limiting lugs or fingers 14 are also bent at their bases and project at right angles to the main portion of the member 11, but extend or project in the opposite direction from the finger 13 and are in a plane spaced from the plane of the finger 13 a distance equal to the thickness of the part 8, so that when the main part 11 is in the useful position, viz., the position 20 for supporting an end of a shade-roller, as shown in Fig. 2, while its rear side is next to the window-frame, its finger 13 has its base extended through an elected one of the slots 9, from the front side to the rear side of the part 8, and its main part 25 is abutting against one of the adjacent keepers, while the fingers 14 are flat against the front side of the part 8 of the base-member 5. It is seen therefore, that the member 11 cannot move away from the shade roller (indicated in broken lines), 30 because of the combined resistance of the fingers 13 and 14; but when the shade-roller is removed, the member 11 can be very easily swung from the position shown in Fig. 2 to that of Figs. 3 and 4, then moved laterally away from the base-member 35 so as to disengage the finger 13 from between the keepers 10; and by the reverse movements, the member 11 can be re-engaged with any pair of keepers the user may select for the desired 40 adjusted position of the member 11.

50

55

In the modified form, Fig. 5, the feet 6 are provided with spurs 5a to be driven into the plate p as auxiliary fasteners. When the bases are provided with such spurs, one screw will suffice; 5 in fact, one foot 6 will suffice where the spurs or one spur and a screw are used in such single foot; and the same is true if two screws are used in one foot which has no spur. It is evident, therefore, that the invention is not confined to 10 the precise details of construction and arrangement as here shown, for the invention is susceptible of numerous changes within the scope of the invention ideas as implied and claimed.

What I claim as my invention is:

15 15 In a shade-roller-bracket, a base-plate which is provided with means to secure its rear side to a window-frame and which is formed with a horizontal row of substantially parallel keepers that are separated by parallel slots through this base 20 plate from the rear to the front side thereof, in combination with an entirely rigid shade-roller-connecting member which includes an angular

attaching finger that has its main part projecting laterally from one side of the main portion of this shade-roller-connecting member which latter includes a stop or limiting element that projects laterally from the side opposite to that of the attaching finger and is parallel with the latter, said limiting element being properly spaced from said main part of the attaching finger to permit the thickness of said base-plate to be disposed therebetween, said main part of the attaching finger being normally flat against said rear side of the base-plate while the limiting element is normally against said front side, said attaching finger having a portion normally extending through and removable from an elected one of said slots and being cooperative with said main part of the attaching finger and said limiting element for securing the shade-roller-connection in one of the elected useful positions, substantially as specified. 10 15 20

GEORGE N. MEDINGER.
